UNITED STATES PATENT OFFICE.

GARRET H. WARD, OF TILLAMOOK, OREGON.

COMBINATION MANGER AND FEED BOX.

Application filed December 7, 1922. Serial No. 605,420.

To all whom it may concern:

Be it known that I, GARRET H. WARD, a citizen of the United States, residing at Tillamook, in the county of Tillamook and 5 State of Oregon, have invented certain new and useful Improvements in Combination Mangers and Feed Boxes; and I do hereby declare the following to be a full, clear, and exact description of the invention, such as 10 will enable others skilled in the art to which it appertains to make and use the same.

This invention relates to a combination manger and feed box.

It is aimed to provide a feed box which 15 may function as usual as in feeding grain to cows, horses or other animals, which is disposable, when not functioning as usual, so that it will not catch refuse or undesirable matter contained in hay and the like, 20 and in the latter position will constitute a wall of a manger.

Another object is to provide a construction of feed box, preferably pivoted, so as to be swung into a feeding position and out of 25 a feeding position so that in its latter position it will serve as a wall of a manger, preferably in combination with plates on the box, to bridge the spaces between the box and side walls of the manger.

30 A third object is to provide a construction in which a pivoted feed box has a rest or support adapted to automatically fold against the box in the normal position of the latter and to automatically unfold and 35 position itself in the second position of the box.

Still another object is to provide the box with a bottom extended beyond its rear inclined wall to directly engage a support beyond such wall and to better confine material in the manger.

Additional objects and advantages will become apparent from a consideration of the description following taken in connection 45 with accompanying drawings illustrating one practical embodiment.

In said drawings:—

Figure 1 is a side elevation of the invention in connection with the stanchion of a 50 cow stall showing the feed box in position forming a wall of the manger in dotted lines and in a feeding position in full lines;

Figure 2 is a front elevation of the stall, illustrating the feed box in a feeding position;

Figure 3 is a rear elevation;

Figure 4 is a cross section on line 4—4 of Figure 2, and

Figure 5 is a cross section on line 5—5 of 60 Figure 1.

Like reference characters designate like or similar parts in the different views.

In reducing the invention to practice, one or more feed boxes 10 are utilized which may be of any suitable size, material, shape 65 or construction. The front wall 11 extends below the bottom wall 12 of the feed box and hinges 13 of any suitable design are secured to cleats 14 fastened to wall 11 which are also secured to a base bar 15, it being understood that the pintles of the hinges 13 are horizontal so that the feed box 10 may be 70 swung in a vertical plane.

The bottom wall 12 extends rearwardly beyond a rear inclined wall 16 as at 17 and 75 sides or plates 18 are secured to wall 12 and terminate short of the rear edge of wall 12 as the latter wall at times is adapted to be supported on a rear support or bar 19 or the equivalent.

80 A prop or support 20 is hinged at 21 to the front of wall 11 and when the box 10 is elevated automatically swings or folds against it, in Figure 4 and when the box 85 is lowered automatically swings outwardly and positions itself as in the dotted line position of Figure 1. A reinforcing cleat 22 is fastened to walls 12 and 14.

90 In order that the function and operation of my improvements may be understood, the same have been shown in connection with a stanchion 23, which for example may be a cow stanchion disposed in a stall as usual but it is to be understood that a limitation 95 in this connection is not to be implied.

100 It will be seen that the feed box 10 may assume a position with the bottom 12 at 17 resting on the bar or support 19 in order that grain or other feed may be placed in the box for access by the cow or other animal which is positioned on the side of the stanchion 23 opposite to box 10 and whose head passes through the stanchion. The space in front of the stanchion forms a 105 manger to receive hay and the like. As the box 10 only holds a limited quantity of the hay and due to its being imperforate also collects the undesirable matter therefrom if the hay were placed directly therein, box 110 10 is capable of being swung to another position, as particularly shown in dotted lines in Figure 1, whereby the manger

110

space is exposed and the bottom 12 constitutes a front wall therefor, enabling more hay to be accommodated and the undesirable matter to sift through the hay. In this 5 manner, the boxes may be kept clean or free of undesirable matter at all times. Extension 17 enables the material to be retained in the manger better than by inclined wall 16 and the height of the manger to be increased. 10 In the position of Figure 1, plates 18 bridge the space between the feed box and side walls 24 of the manger.

In feeding animals, the manger may be filled with hay and the box 10 disposed there-over and filled with grain. The animal, particularly a cow, after eating the grain will by means of the nose tilt the box 10 from the full line to the dotted line position as best shown in Figure 1 to gain access to 20 the hay.

As merely one practical embodiment has been illustrated and described, it is to be understood that changes in the details may be resorted to provided they fall within the 25 spirit and scope of the invention.

I claim as my invention:—

1. A feeding apparatus consisting of a feed box, means pivotally mounting said box whereby it may be swung from a feeding 30 position to another position to constitute a wall of a manger, and means on the feed box to bridge the exposed space between its sides and the sides of the manger in the latter position.

35 2. A feeding apparatus consisting of a feed box having a side wall depending below the bottom wall in the normal position thereof, means to which said box is pivoted adjacent the base of said side wall, the end 40 walls of the box projecting beyond the rear wall of the box, said box being adapted to swing upon its pivot whereby said bottom wall will constitute a wall of the manger, and the extensions of the end walls will

bridge the spaces between the box and the 45 manger.

3. A feeding apparatus consisting of a feed box, said box having a front inclined wall, said box having a bottom wall extending outwardly beyond said inclined wall, the side wall of the box opposite to said inclined wall extending below the bottom wall, means pivoting the latter side wall below the bottom wall whereby the box may be swung from a feeding position to another position in which the bottom constitutes the wall of the manger, a support engageable by said bottom adjacent its extended end portion when in a feeding 50 position, plates carried by the box to extend at an angle from the box in the latter position 55 so as to constitute sides of a manger.

4. A feeding apparatus consisting of a feed box, said box having a front inclined wall, said box having a bottom wall extending outwardly beyond said inclined wall, the side wall of the box opposite to said inclined wall extending below the bottom wall, means pivoting the latter side wall below the bottom wall whereby the box may 60 be swung from a feeding position to another position in which the bottom constitutes the wall of the manger, a support engageable by said bottom adjacent its extended end portion when in a feeding position, and plates extending from the said bottom wall terminating short of the ends of said bottom 65 adjacent said inclined wall and adapted in the second mentioned position of the box to bridge the spaces between its sides and the 70 sides of the manger.

In testimony whereof I affix my signature in presence of two witnesses.

GARRET H. WARD.
